A. DADE.
LIQUID DISPENSING APPARATUS.
APPLICATION FILED MAR. 12, 1913.

1,088,261.

Patented Feb. 24, 1914.

UNITED STATES PATENT OFFICE.

ALBERT DADE, OF FRANKFORT, NEW YORK.

LIQUID-DISPENSING APPARATUS.

1,088,261.

Specification of Letters Patent.

Patented Feb. 24, 1914.

Original application filed May 21, 1912, Serial No. 698,695. Divided and this application filed March 12, 1913. Serial No. 753,807.

To all whom it may concern:

Be it known that I, ALBERT DADE, a citizen of the United States, residing at Frankfort, in the county of Herkimer and State 5 of New York, have invented certain new and useful Improvements in Liquid-Dispensing Apparatus; and I do hereby declare the following to be a full, clear, and exact description of the invention, such as will enable others skilled in the art to which it 10 appertains to make and use the same.

This invention relates to liquid dispensing apparatus, and is a division of my application Serial No. 698,695, filed May 21, 1912.

15 An object of the invention is to provide an improved beverage-dispensing apparatus, associated with an airtight cask or container, for forcing the beverage from the container by air pressure.

20 A further object of the invention is to provide for aerating the beverage both before drawing the beverage from the container and during said operation.

Another object of the invention is to provide 25 an apparatus of this character which may be quickly and easily knocked down or dismembered, for transportation and storage.

Another object is to provide an apparatus 30 of this character which is simple of construction and operation, easy to manipulate, and thoroughly practical and efficient in operation.

Other objects and advantages may be 35 cited hereinafter and in the claims.

In the accompanying drawings, which 40 supplement this specification, Figure 1 is a vertical sectional view through a container associated with the device which constitutes my invention, the latter being shown in side elevation. Fig. 2 is a vertical sectional view through the pump and its adjuncts, and, Fig. 3 is a vertical sectional view through the draft tube and the valve member associated therewith.

45 In these drawings, in which similar reference characters correspond with similar parts throughout the several views, the elements which are shown in section above the cask 5 in Fig. 1 form no part of the present invention, but the invention consists essentially of the said draft tube 6, the downwardly tapered and centrally apertured plug 7, the coil 8, the air pump 9, the air pipe 10, the valve 11, the connection 12, and

faucet 13. In the connection 12 is formed the upper liquid duct 14 and the upper air duct 15, the said connection 12, at 16 for engagement with the pump 9, and at 17, 18 and 19 for engagement with the pipes 10 and 8^a and the faucet 13, respectively. The plug 7 is in screw threaded engagement with a hollow nipple 20, which latter is connected to the lower end of the air pipe 10 by means of a coupling member 21. 60 A flexible valve 11 is secured on the inner end of the nipple 20 and projects into the draft tube 6 through the aperture 6^a, in the wall of the said draft tube. The valve is split at 22, and is preferably made of 70 rubber, so that air may pass from the nipple through said valve into the draft tube 6, but fluid is prevented from returning through the valve 11 by means of its peculiar construction which causes it to close when pressure is applied on the convex surface thereof.

The elements 6, 11, 20, 10 and 15 constitute a continuous air passage from the pump 9 to the cask 5, while the elements 6, 8, 8^a, 14 and 13 constitute a continuous fluid passage from the cask to the outer air; and so, it will be seen that the draft tube 6 is alternately employed as an air duct and as a liquid duct. Ice or other cooling substance 85 may be packed around the coil 8 for cooling the beverage while it is being dispensed.

The pump 9 may be of any proper and desirable form or kind for forcing air through the air passage into the cask. The 90 plug 7 may be forced into the bung hole of the cask and rendered air tight therein by any suitable means, while the draft tube 6 may be snugly fitted through the central aperture of the plug 7, and any suitable 95 packing 23 may be held in place by a nut 24 for providing an air-tight joint between the plug 7 and tube 6.

In practice, this apparatus may be employed for dispensing beer, cider, wine, or 100 other beverages, but it is more particularly designed for such beverages as require to be aerated, or which are improved by aeration while being dispensed.

In operation, the faucet 13 remains closed 105 and air-tight at all times except when the beverage is being drawn therethrough, so that when the pump 9 is operated, it forces air down through the air passage (described) into the cask, through the opening 110

25, and the air, being lighter than the liquid, rises to the surface of the liquid in the top of the cask, and as more air is pumped into the cask, it becomes sufficiently compressed 5 above the surface of the liquid to force said liquid or beverage through the liquid passage when the faucet is opened. Now, it will be seen that as the air passes up through the liquid from the opening 25, it aerates 10 the liquid to a certain extent, and when certain liquids are being dispensed, a foam is formed upon the surface of the liquid, but this foam does not pass out through the liquid duct until the cask becomes nearly 15 empty.

Now, it is well known that certain liquids are not considered desirable unless they are accompanied by a considerable amount of foam when drawn, and in order to create 20 such foam, even when the cask is approximately full, the pump may be operated while the faucet 13 is open, so that the air enters the tube 6 while the liquid is passing upward therethrough, and mixes with the 25 liquid as it passes through the coil, so that foam is formed while the liquid is being dispensed. The amount of foam may be varied according to the amount of pumping that is done while the liquid is being drawn, and 30 in some instances, it may be sufficient to operate the pump slightly and only just before the glass or other receiving vessel is filled.

It will be seen that I have provided a 35 liquid dispenser of this character which is fully capable of attaining the foregoing objects in a thoroughly practical and efficient manner.

I do not limit my invention to the exact 40 details of construction, combination and arrangements of parts as herewith illustrated and described, but my invention may only be limited by a reasonable interpretation of the claims.

45 I claim:

1. In a liquid dispensing apparatus, the combination with a container having a bung hole therein, of a plug adapted to be fitted

into the bung hole, a draft tube extending through the plug into proximity with the 50 bottom of the container, a pump, an air pipe communicating with the pump and with the draft tube, a check valve for preventing fluid from passing from the draft tube to said air pipe, and a faucet communicating 55 with the draft tube exteriorly of the container.

2. In a liquid dispensing apparatus, a liquid container, a draft tube extending into the container for drawing liquid from the 60 container, means for establishing and interrupting the flow of liquid through the draft tube, an air pipe communicating with the draft tube, and means for forcing air through the air pipe and through a portion 65 of the draft tube into the container and thereby creating air pressure on the liquid for forcing it through the draft tube past the air pipe while air is being forced through the air pipe into the liquid duct, so 70 as to aerate the liquid while it is being dispensed.

3. In a liquid dispensing apparatus, a liquid container, a draft tube extending into the container and having means associated 75 therewith for establishing and interrupting the flow of liquid therethrough, an air pipe communicating with the draft tube, and means for forcing air through the air pipe and through a portion of the draft tube 80 into the container while the flow of liquid is interrupted, for creating air pressure in the container and thereby forcing liquid through the draft tube past the air pipe when the flow of liquid is uninterrupted and 85 for forcing air into the draft tube, so that air and liquid are caused to mix within the draft tube while the liquid is being dispensed.

In testimony whereof I have signed my 90 name to this specification in the presence of two subscribing witnesses.

ALBERT DADE.
